DAVID H. TILLERY AND THOMAS H. TILLERY, OF NEWARK, NEW JERSEY.

TRIPPING ATTACHMENT FOR CLOCKS.

1,214,843.

Specification of Letters Patent.

Patented Feb. 6, 1917.

Application filed January 12, 1916. Serial No. 71,617.

To all whom it may concern:

Be it known that we, DAVID H. TILLERY and THOMAS H. TILLERY, citizens of the United States, and residents of Newark, county of Essex, and State of New Jersey, have invented certain new and useful Improvements in Tripping Attachments for Clocks, of which the following is a specification.

10 This invention relates to an attachment for a clock which can be either permanently or removably attached to a clock so that the clock, which has an ordinary time-released device similar to an alarm clock, 15 can be utilized for the purpose of releasing any desired mechanism at a predetermined time. Clocks of this kind are used at present for releasing the damper and draft regulating mechanisms of furnaces, 20 heaters and the like, for releasing electric switches for causing the lighting or extinguishing of lights on light circuits in stores, and in other situations where a desired function is to be performed in the absence 25 of any individual. Clocks of this kind have been made with means connected with the clock to bring about this result, but heretofore they have been made as part of the clock, or so disposed as to put a strain on 30 the gear train of the clock so that the clock is interfered with in its time keeping properties, and in the case of breakage, requiring the services of a skilled workman to repair it.

35 The present invention is designed to provide an attachment which is shown as attached to an ordinary type of alarm clock, such attachment being disposed on the clock so that it is operated by the time-released 40 device and is adapted to support a weight or other device suspended by said means so that the major portion of the strain comes on the clock casing and not on the works inside of the clock.

45 The invention is further designed to provide an attachment of this kind which can be easily attached to or detached from the clock, is cheaply manufactured and is easily set so as to be operative when released by 50 the time-released device.

The device is removable so that in case of breakage of the clock, or for any reason the clock is out of order, the device can be removed and attached to another clock, 55 these clocks being at present on sale on the market at an extremely low cost, whereby

it is possible to thus replace an old clock with a new one at less expense than is entailed in the repair of the special clocks now in use in this connection.

60 The invention is illustrated in the accompanying drawing, in which Figure 1 is a rear view of an ordinary alarm clock with the attachment set and supporting an element to be tripped. Fig. 2 is a side view 65 of the structure illustrated in Fig. 1. Fig. 3 is a perspective view of one of the bearing plates used in the invention, and Fig. 4 is a perspective view of a modified form of lever and bearing therefor.

70 The form of clock shown consists of an ordinary circular casing 10 in which the clock works are inclosed and having a post 11 at the top which is usually provided with an alarm bell 12 and is also usually provided with a ring 13 at the top. It will be understood that any other form of supporting means for the clock can be employed and it is suspended by said supporting means on any suitable structure, such as a 75 hook 14. The clock has, projecting from the back thereof, suitable handles, such as a handle 15 which is for the purpose of setting the hands, the handle 16 for winding up the clock, a handle 17 for setting the 80 time released device to govern the time when it is to be released, and a winding handle 18 for the alarm attachment, which handle is turned in one direction to wind it, and is turned backward in the reverse direction when the time-released device is 85 tripped, and this is utilized for the purpose of releasing the attachment herein described. The usual form of alarm clock is supported on the bottom edge and also on 90 two feet 19 which project at angles from the lower part of the casing on each side of the center of the clock as clearly shown in Figs. 1 and 2. These feet are utilized for holding the attachment to the clock.

95 In the form shown in Figs. 1, 2 and 3 bearing plates 20 are provided with slots 21 to form the hooks 22 on the ends of the bearing plates, these hooks being caught over the feet 19 in such a way that the 105 right-angled or bearing parts 23 of the bearing plates are opposed to each other. The bearing plates serve to support a suitable pivot 24 which in the case illustrated is a screw provided with a nut 25 so that 110 the distance between the bearing plates can be regulated and then can be drawn to-

gether to bring their hooked ends in tight engagement with the feet 19 in different makes of clocks in which the feet are various distances apart. The pivot 24 acts as a fulcrum for a lever, the illustration showing a lever made of wire, the lever 26 being bent into a series of coils or convolutions 27 through which the pivot 24 passes, the lever 26 being bent in a substantially curved direction, as at 28, and being provided with means, such as an eye 29, for receiving one end of the spring 30 which is securely attached thereto, the other end of the spring 30 being secured to a tripping plate 31 which can be made in many different forms to embrace the winding key 18, but the type shown consists of separated ends 32 which are bent over to form the fingers 33, which fingers rest on each side or extension of the winding key 18. The wire of the lever, after it is formed into the coil 27, extends downward and forms the right-angled extension 34 so that the whole lever partakes of the nature of a bell crank, the extension 34 being bent into the hook part 35 or into any other suitable form of means for supporting the element to be tripped. This element in the illustration comprises a ring 36 fastened to a suitable strand 37 which extends to any suitable point where the releasing is to be accomplished, in the case of a heater, for instance, being fastened to the diaphragm lever of the heater, or it can be used to support a weight, the weight when released in turn acting to operate the device to be tripped. These installations are not illustrated, since they are very common and of many kinds and it is within the knowledge of any person to attach or locate the clock in any desired position to perform the functions required of it.

When the clock is in position and is wound so that it runs, the winding key 18 is turned to wind up the alarm or what is known in this specification as the time-released device, usually being fixed or halted in a horizontal position as it is shown in Figs. 1 and 2. The ring 36 is then caught onto the hook part 35 of the extension 34 of the lever, and the tripping plate is then caught over the rings of the winding key 18, the spring being put under suitable tension to accomplish this, the spring in turn acting to hold the tripping plate 31 in place. When so supporting an element, such as the ring 36 with the strain that is upon it, the present attachment supports the lever from the casing of the clock by reason of the attachment of the bearing plates to the feet 19, and the casing of the clock in turn being supported from the hook 14 or other suitable supporting element, the clock casing transmits or takes up the strain of such supporting and

there is no severe strain on the works of the clock, only sufficient strain being there to hold the tripping plate 31 firmly against the winding key 18. When the alarm part or time-controlled device is released, the winding key 18 begins to turn in reverse direction from which it turned when it was wound, and it thus throws the tripping plate off, which permits the weight suspended by, or acting to pull down on, the ring 36, to swing the lever so that the ring 36 slides from the hook 35. Of course it will be evident that other forms of device can be devised to fit different forms of clocks or the ordinary type of alarm clock, and that different forms of bearing plates or tripping plates can be used without departing from the scope of this invention.

In Fig. 4 is illustrated a modified form of support for the lever, the support in this form comprising a wire strand which is formed at its center to provide the pivot 38 with the upright parts 39 flanking it, the curved parts 40 extending beneath the clock and having the ends 41 which can be bent around the feet 19 and firmly pressed around the feet so as to hold the device to the clock.

This device is designed more particularly for locations where the fixture is to be attached to the clock without any anticipation of the necessity for easy removal.

Having thus described our invention, we claim:

1. The combination, with a clock having suspending means at its top and comprising an alarm winding key, of means for releasably supporting an object from and beneath the clock and substantially in line with the clock suspending means, and means on the clock and operated by the alarm winding key of the clock for releasing an object so supported.

2. An attachment for alarm clocks comprising a lever, a pivot for said lever, means for detachably securing said pivot to the clock casing by engagement with the legs thereof, a supporting hook on the lever, and a connection on the lever for engaging the alarm winding key of the clock.

3. An attachment for alarm clocks comprising a lever, a pivot for said lever, means for detachably securing said pivot to the clock casing, a supporting hook on the lever and beneath the clock, a tripping plate, and a spring connecting the lever and the tripping plate.

4. An attachment for alarm clocks comprising a lever, a pivot for said lever, means for detachably securing said pivot to the clock casing, a supporting hook on the lever and beneath the clock, a forked tripping plate with bent ends on said forks, and a spring connecting the lever and the tripping plate.

5. An attachment for alarm clocks comprising bearing plates with hook ends, the hooks being adapted to engage with the legs on the clock casing, means for drawing the bearing plates toward each other, and a lever pivoted between the bearing plates. 20
6. An attachment for alarm clocks comprising bearing plates with hooked outer ends, a screw connecting the plates to draw them toward each other, a lever swinging on the screw, a supporting means on the lever, a spring on the lever, and a tripping plate attached to the spring. 25
7. An attachment for alarm clocks comprising bearing plates with hooked outer ends, a screw connecting the plates to draw them toward each other, a lever swinging on the screw, a hook end on the lever, a spring secured to the end of the lever, and a 30

tripping plate secured to the spring, the tripping plate having a forked end.

8. An attachment for alarm clocks comprising means adapted for engaging the legs of the clock, means for drawing said engaging means toward one another, said last-named means serving also as a pivot, a lever turning on said pivot, a supporting means on said lever adapted for release of the object supported by the turning of said lever, and holding means for said lever adapted to be releasably connected to the alarm winding key of the clock. 35

In testimony that we claim the foregoing, we hereto set our hands, this 10th day of January, 1916.

DAVID H. TILLERY.
THOMAS H. TILLERY.
